US0D1102121S

(12) **United States Design Patent** (10) Patent No.: **US D1,102,121 S**
(45) Date of Patent: ** Nov. 18, 2025

(54) **SHOE SOLE**

(71) Applicant: **Zejun Hu**, Shenzhen (CN)

(72) Inventor: **Zejun Hu**, Shenzhen (CN)

(**) Term: **15 Years**

(21) Appl. No.: **29/929,066**

(22) Filed: **Feb. 19, 2024**

(51) LOC (15) Cl. **02-04**

(52) U.S. Cl.
